(57) **CLAIM**

The ornamental design for a side and end deflector for solar panel, as shown and described.

DESCRIPTION

Side and end deflectors for solar panel made according to the invention are typically used along the sloped side and along the raised back end of a sloped solar panel at the end of a row of sloped solar panels.

FIG. 1 is a top, front, right side isometric view of side and end deflectors for solar panel showing my new design;

FIG. 2 is a front elevational view thereof;

FIG. 3 is a right side elevational view thereof;

FIG. 4 is a left side elevational view thereof; and,

FIG. 5 is top plan view thereof.

The broken line showing of the environment is for illustrative purposes only and forms no part of the claimed design.
